THE SECTION FOR CONNECTING ADJACENT LADDER SCAFFOLDS

Thomas C. North, Zelienople, Pa., assignor to Universal Manufacturing Corp., Zelienople, Pa., a corporation of Pennsylvania

Application June 8, 1949, Serial No. 97,734

2 Claims. (Cl. 304—39)

1
This invention relates to ladder scaffolds, and more particularly to units or sections for tying together parallel scaffolds.

It is among the objects of this invention to provide a tie section for connecting parallel ladder scaffolds which is adjustable in length, which can be separated into small compact units that can be more readily stored or transported, which can be quickly and easily connected to and disconnected from the scaffolds that it ties together, and which is strong enough to support a working platform between the scaffolds.

In accordance with this invention, the tie section includes a horizontal spreader member which is adapted to span the space between the two vertical end panels located at one end of the parallel ladder scaffolds which the tie section is designed to connect. Hooks are connected to the opposite ends of the spreader member and extend lengthwise of it out past the adjacent panel legs and then across the tops of a pair of the panel rungs in engagement therewith and then down the opposite side of each rung. In this way the tie section is supported by the rungs which are engaged by its hooks, and the connected end panels are prevented from moving toward or away from each other. The spreader member preferably is formed from the aligned upper members of two triangular elements disposed in the same vertical plane where they are adjustably connected by a connecting member. Each triangular element also has a vertical side member next to a panel leg, and an inclined brace connecting the lower end of the side member to the inner end of the upper member. The hooks are mounted at both the upper and lower ends of the vertical side member. A truss is thus formed which is adjustable in length and which is strong enough to support a working platform between the scaffolds.

The preferred embodiment of the invention is shown in the accompanying drawings, in which Fig. 1 is an end view of two parallel scaffolds whose ladder panels are connected by my tie section; Fig. 2 is a combined plan view and horizontal section taken on the line II—II of Fig. 1; Fig. 3 is a vertical section through one of the ladder panels, taken on the line III—III of Fig. 1; and Fig. 4 is an enlarged fragmentary plan view of a detail, taken on the line IV—IV of Fig. 1.

Referring to the drawings, a pair of parallel ladder scaffolds 1 and 2 are shown. Each scaffold is formed from a pair of parallel vertical end panels connected by a vertically adjustable

2
platform 3 and reinforced by inclined braces 4. The platform structure is described in detail and claimed in my copending patent application, Serial Number 91,350, filed May 4, 1949. The drawings herein show only one end panel of each scaffold, but it will be understood that the panels at the opposite end of the scaffolds are the same as the ones shown. Each end panel has legs 6 which are connected by equally spaced rungs 7 so that the panel resembles a ladder and serves as one to a certain extent. Each end panel may be formed from one or more superimposed ladder sections, depending upon the height of the scaffolding desired.

20
In accordance with this invention, the two end panels shown, which are located at one end of the pair of parallel scaffolds, are connected by a tie section 8. The two end panels (not shown) at the opposite end of the parallel scaffolds are connected in the same way. Each tie section preferably is in the form of a truss which spans the space between the end panels at its opposite ends. The horizontal member of the truss has its ends substantially abutting the inner legs 6 of the end panels, and it thereby serves as a spreader which prevents the panels from moving any closer together. The spreader is formed from a pair of longitudinally spaced tubes 11 which are connected by a central connecting member 12 that is telescoped into the inner ends of the tubes. Fastening members, such as bolts 13, extend through transverse holes near the inner ends of the tubes and through registering holes extending transversely through the connecting member. By providing the latter with a plurality of longitudinally spaced holes 14, it can be telescoped different distances into the tubes and locked in those positions by bolts 13, thereby varying the length of the spreader member in accordance with the distance between the scaffolds.

40
Each tube 11 forms the top of a triangular element. One side of the triangle is formed from a vertical side member 16 that extends from the outer end of the tube down along the adjacent end panel leg. The third side of the triangle is formed from an inclined brace 17 that is secured to the inner end of the horizontal tube and to the lower end of the vertical side member. The lower end of this brace substantially abuts the adjacent leg of the end panel. It will be seen that both triangular elements and the two end panels all lie in the same vertical plane.

The truss just described is connected to and supported by the vertical end panels by means of hooks 18 attached to its opposite ends. Prefer-

ably, there are hooks at the upper and lower ends of each vertical side member 16 of the truss. Each hook is formed from a short metal rod. Each upper hook has its inner end welded to one side of the outer end of the adjoining horizontal tube 11, and projects lengthwise of that tube out beyond its end. More specifically, the hook extends past the adjacent panel leg 6 and then is bent at substantially a right angle so that it will extend across the top of a panel rung 7 on which it rests for support. The outer end portion of the hook is bent to extend downward across the rung. It will be seen in Fig. 2 that the panel leg is held in the recess formed between the end of the spreader member and the horizontal portions of the hook extending around two sides of the leg. The lower hooks of the tie section are the same as the upper hooks, but their inner ends are welded to the sides of the lower ends of the inclined braces 17. The distance between the vertically spaced hooks at each end of the tie section is such that both of them will rest on different rungs of the adjoining ladder panel. In other words, they are spaced the same distance apart as the rungs, or a multiple of that distance, depending on the depth of the truss. The hooks not only support the truss from the scaffold end panels, but they also prevent the panels from moving farther apart.

It will be seen that each tie section is a strong truss which can support one end of a working platform that can be laid across the tie sections to enable workmen to do overhead work between the scaffolds. The tie section can be removed from the supporting end panels by merely lifting it far enough for its hooks to clear the adjoining rungs, and then swinging it horizontally to move the hooks away from the panels. When the tie section is not being used, the central member 12 that connects the two triangular elements can be removed so that the triangular elements can be placed flat against each other for storage or transportation.

According to the provisions of the patent statutes, I have explained the principle of my invention and have illustrated and described what I now consider to represent its best embodiment. However, I desire to have it understood that, within the scope of the appended claims, the invention may be practiced otherwise than as specifically illustrated and described.

I claim:

1. A tie section for connecting a pair of par-

allel ladder scaffolds having vertical end panels each provided with a pair of legs connected by tubular rungs having their ends flattened in a vertical plane to form lateral recesses where they join the legs, said section comprising a truss adapted to span the space between the two end panels located at one end of the parallel scaffolds, and vertically spaced hooks connected to each end of the truss, each hook being a bent rod extending lengthwise of the truss past the adjacent panel leg and then across the top of a panel rung in engagement therewith and down the opposite side of the rung in one of said recesses, whereby the truss will be supported by the rungs engaged by its hooks.

2. A tie section for connecting a pair of parallel ladder scaffolds having vertical end panels each provided with a pair of legs connected by tubular rungs having their ends flattened in a vertical plane to form lateral recesses where they join the legs, said section comprising a horizontal spreader member adapted to span the space between the two end panels located at one end of the parallel scaffolds, braces having upper ends secured to the spreader member and having lower ends directly below the opposite ends of said member, hooks connected to the opposite ends of the spreader member, and similar hooks connected to the lower ends of the braces, each hook being a bent rod adapted to extend past the adjacent panel leg and then across the top of a panel rung in engagement therewith and down the opposite side of the rung in one of said recesses, whereby the tie section will be supported by the rungs engaged by its hooks.

THOMAS C. NORTH.
